UNITED STATES PATENT OFFICE.

WILLIAM J. HALLOCK, OF JERSEY CITY, NEW JERSEY.

SUBMARINE BOMB.

1,183,375.

Specification of Letters Patent.

Patented May 16, 1916.

Application filed December 18, 1915. Serial No. 67,514.

To all whom it may concern:

Be it known that I, WILLIAM J. HALLOCK, a citizen of the United States, residing at Jersey City, in the county of Hudson and State of New Jersey, have invented a certain new and useful Improvement in Submarine Bombs, of which the following is a specification.

The invention relates to bombs designed to be dropped by an aviator into the water above or in proximity to an object of attack or beneath the surface, and to be exploded by the action of the water upon a detonating device.

The object of the invention is to provide a bomb of this character which may be exploded at or near the surface of the water or at any predetermined depth; which may be quickly conditioned to explode at the desired depth, and when not thus conditioned may be carried in the flying machine or airship without danger of accidental explosion.

The invention consists in certain novel features of construction and arrangement by which the above objects are attained, to be hereinafter described and claimed.

The accompanying drawings form a part of this specification and show a structure embodying the invention.

Figure 1 is a side view of the bomb, a portion being shown in vertical section. Fig. 2 is a plan view of the base of the bomb. Fig. 3 is a corresponding plan with the base-cover removed. Fig. 4 is a vertical axial section taken on the line 4—4 in Fig. 2.

Similar letters of reference indicate the same parts in all the figures.

The bomb is preferably cylindrical and of considerable length proportionally to its diameter, having a pointed end or head A to facilitate its rapid descent through the air and water, and having the body portion B equipped with longitudinal wings or vanes B¹ serving to maintain the bomb in a vertical position during such descent. The base C of the bomb is hollow to provide a chamber c separated from the body B by a horizontal partition or deck C¹, and closed by a cover D screwed upon the base. In the chamber is a centrally located annular partition or wall E terminating a short distance below the cover D to form an open cup-like recess or pocket e on the upper face of the deck. On the under face of the deck is an annular flange C² screw-threaded exteriorly to receive the body B, and in-

teriorly to receive a cup or shell F forming a chamber f below the deck containing batteries M and having an insulating plug F¹ in its bottom through which the electric wires are led to a detonator or cap N constructed to explode the charge in the bomb by the completion of the electric circuit as usual.

Through the sides of the partition E extend two oppositely located electrodes or contact-points M¹ M¹ mounted in adjustable insulated plugs M² M² connected by wires extending through the deck C¹ to the batteries and detonating cap so that the latter will be fired when the circuit is completed between the electrodes M¹ M¹.

In the sides of the base C are openings c¹ c¹ through which water may enter the chamber c when one or both of the screw-plugs C³ C³ are removed and the bomb is submerged. Deflecting plates C⁴ C⁴ arranged above the apertures c¹ c¹ tend to drive the water rapidly through the latter and into the chamber c while the bomb is descending through the water.

D¹ D¹ are hollow bosses or nipples on the cover D having radial openings d controlled by a rotatable plate D² having radial openings corresponding to the openings d, by which the effective area of the latter may be varied and the volume or rapidity of the flow of water therethrough to the chamber c may be controlled or varied. The screw-caps D³ D³ serve to close the nipples tightly when required.

In the center of the cover D is a boss D⁴ through which a screw G extends axially, operated by a hand-wheel G¹ exterior to the cover, and carrying at its lower end a disk G² and gasket G³ adapted to be forced down upon the open upper end or rim of the annular partition E and close the chamber or pocket e against the entrance of water, and by retracting the screw, to permit the annular passage between such rim and disk to be adjusted or varied.

In exploding the bomb the aviator removes one or more of the screw-plugs C³ C³ and caps D³ D³ and retracts the disk G² sufficiently to condition the chamber c to fill with water to the level of the partition E at the moment the bomb has reached the desired predetermined depth in its downward travel through the water, as previously determined by experiment or calculation. The bomb is then dropped and the chamber c

partially fills with water which overflows into the pocket *e*. When the water in the pocket reaches the electrodes *M*¹ *M*² it bridges the space between them and by its inherent conductivity completes the circuit through the detonating cap *N* and the explosion follows.

It is important that the bomb descend in an approximately vertical position. This may be attained by any suitable means, that shown being the above-mentioned vanes *B*¹ which by the action of the air and water thereon tend to maintain the bomb in the upright position in which it is launched. The vanes are shown as each having a flange *B*² extending at each end beyond the body portion of the wing and bent inwardly at the front or lower end to form a hook *B*³ engaged in a suitable cavity formed on the body *B* of the bomb, and at the upper or rear end engaged within a clamp or band *H* encircling the body at its junction with the base *C* and clamped tightly by the screw *H*¹ engaged in the lugs *H*² *H*³ on the separated ends of the band.

If the bomb is to be exploded at a considerable depth, only one of the screw-caps *D*² is removed and the plate *D*² turned to admit water slowly to the chamber *c*, and for less depths the plate is opened farther or both caps removed and the plates set to admit water more rapidly. The flow to the pocket *e* may be further governed by the position of the disk *G*² relatively to the rim of the annular partition *E*, or one or more of the caps and plugs may be removed from the nipples and openings to admit water freely and the depth at which the explosion will take place may be controlled by the position of the disk *G*² alone, or other easily operated means may be adopted for controlling the ingress of water to the chamber *c* and thence to the pocket *e*. By tightly closing the nipples and openings and forcing the disk *G*² to its seat on the partition *E*, as an additional safeguard, the chamber *c* and pocket *e* are tightly sealed and the bomb thus rendered harmless even though submerged as may occur by the descent of the flying machine or airship upon the surface of the sea either by accident or design.

I claim:

1. A bomb adapted to be dropped from the air into water and having a chamber therein with an opening arranged to admit water to such chamber, a pocket in said chamber, exploding means in said pocket actuated by the ingress of water from said chamber to said pocket, and means for controlling the flow of water from such chamber to such pocket.

2. A bomb adapted to be dropped from the air into water and having a chamber

therein with an opening arranged to admit water to such chamber, a pocket in said chamber, exploding means in said pocket actuated by the ingress of water from such chamber to such pocket, means for controlling the flow of water to such chamber, and means for controlling the flow of water from such chamber to such pocket.

3. In a bomb of the character set forth, a hollow base, a cover therefor forming with said base a chamber in the latter, a partition in said chamber forming a pocket therein, openings in said base to admit water to said chamber, electrodes in said pocket arranged to complete an electric circuit by the ingress of water to such pocket to explode the bomb, and means for controlling the flow of water to such pocket.

4. In a bomb of the character set forth, a hollow base, a cover therefor forming with said base a chamber in the latter, an annular partition in such chamber forming a pocket therein, exploding means in said pocket actuated by the ingress of water to said pocket, said base having an opening from the exterior to said chamber, and a closure for such opening.

5. In a bomb of the character set forth, a hollow base, a cover therefor forming with said base a chamber in the latter, an annular partition in such chamber forming a pocket therein, exploding means in said pocket actuated by the ingress of water to said pocket, said base having an opening from the exterior to such chamber, a closure for such opening, and a deflector above such opening arranged to force water through such opening by the movement of the bomb through water.

6. In a bomb of the character set forth, a hollow base, a cover therefor forming with said base a chamber in the latter, an annular partition in such chamber forming a pocket therein, exploding means in said pocket actuated by the ingress of water to said pocket, said base having an opening from the exterior to said chamber, a disk adapted to close such pocket, and a screw extending through said cover for operating said disk.

7. In a bomb of the character set forth, a hollow base, a cover therefor forming with said base a chamber in the latter, an annular partition in such chamber forming a pocket therein, exploding means in said pocket actuated by the ingress of water to said pocket, said cover having an opening therein for the admission of water to such chamber, and adjustable means for controlling the flow of water through such opening.

In testimony that I claim the invention above set forth I affix my signature.

WILLIAM J. HALLOCK.
